WORK SUPPORTING MEANS FOR SEWING MACHINES

Charles A. Dearborn, New York, N. Y., assignor to American Blind Stitch Machine Company, New York, N. Y., a corporation of New York

Application December 7, 1933, Serial No. 701,297

11 Claims. (Cl. 112—177)

The present invention relates to improvements in overseaming blind stitch sewing machines of the power driven type illustrated for example in the machine of my Patent No. 1,025,082 granted

5 April 30, 1912.

In the years of the development of this type of machine I have produced a machine for blind stitching which operates at a speed of 1500 to 2000 revolutions a minute, such rapidity of operation requiring substantial strength in the design of the machine and great refinement and accuracy in the various parts to enable it to satisfactorily perform a great quantity and fine quality of the desired work.

15 Improvements in the present development of the machine relate to the adjustable work supporting means and the automatic operating mechanism therefor by means of which the depth of the work presented in the path of the needle is periodically changed or adjusted for effecting a succession of deep stitches and intermediate shallow stitches. The deep stitches pass through the several layers of material, such, for instance, as the base material and the folded over portion 20 of a hem that is being sewed, while the shallow stitches pass through the inner edge of the folded over layers only and skip the base material.

25 Machines for performing this general operation have long been known in the art, but the improvements of the present application are of simple and effective construction to apply to the particular power driven type of blind stitch sewing machine referred to above. The number of shallow or skip stitches between the more widely spaced deep stitches depends upon the gear ratio 30 of the operating mechanism which controls the variable position of the work supporting table, it being possible with suitable gearing to provide 1, 2, 3 or more shallow stitches between spaced 35 deep stitches.

40 A further improvement in the mechanism of the present application is in the provision of means by which the automatic mechanism for effecting the periodic changes in the depth of 45 stitches in the work can be thrown out of operation and the machine adjusted to perform uniform blind stitch sewing such as is performed by the well-known blind stitch sewing machines now in use.

45 In order that the invention may be fully understood it will first be described with reference to the accompanying drawings and the novelty afterwards pointed out in the annexed claims.

50 55 In said drawings

Figure 1 is a side elevation of the improved machine embodying the present invention;

Figure 2 is a plan view of the same, parts being broken away for the sake of clearness;

Figure 3 is a vertical longitudinal sectional view taken on the line 3—3 of Figure 2;

Figure 4 is a view similar to Figure 3 showing the parts in a slightly changed position;

Figures 5 and 6 are detail vertical transverse sectional views taken respectively on the section 10 lines 5—5 of Figure 3 and 6—6 of Figure 4;

Figure 7 is a detail horizontal sectional view taken on the line 7—7 of Figure 3;

Figure 8 is a view similar to Figure 1 showing parts in section with the automatic operating 15 mechanism for the work supporting table thrown out of action;

Figures 9, 10, 11 and 12 are detail views illustrating different phases of the work performed by the improved machine.

20 The main frame of the machine of the type to which the present improvements are particularly applicable is formed of a single heavy casting having integral strengthening ribs and comprising essentially a rigid central base 1, centrally perforated for rigid bolting to a work bench, the upwardly extending main arm 2 at the rear terminating in the shaft bearing sleeve 3 from the left of which projects the forwardly extending arm 5 having horizontal bearings 4 for the needle rock-shaft 15. This forward machine arm 5 25 also supports the looper and feed bar in the manner hereinafter referred to.

Extending forwardly and upwardly from the front of base 1 is the integral arm 6 terminating in the sleeve 7 in which is secured the front horizontal bearing shaft or rod 8 upon which is pivoted the work support 40, presently to be described.

main power shaft 10 just inside crank disk 13. This needle operating mechanism is the same as in my former patents.

40 is the work supporting frame formed with 5 the spaced bearing sleeves 41 which are freely journaled upon the oppositely projecting ends of the rod or shaft 8 carried in sleeve 7 in the upper end of frame arm 6. These bearing sleeves 41 rest snugly against the finished vertical side faces 10 of the sleeve 7 which they embrace. Projecting downwardly from one of the bearings 41 is an integral rock-arm 42 engaged at its lower end by a heavy coil spring 43 which extends rearwardly from said arm 42 to one arm of a stout horizontal bell crank lever 44 which is pivoted at 15 45 to the base 1. The other arm of bell crank 44 is engaged by an adjustable screw stop 46 threaded through a rib 1a of the base frame, the described arrangement giving to the pivoted cloth 20 supporting frame 40 a strong spring support to hold it in its normal horizontal working position, which is determined roughly by the adjustable screw stop 47 threaded through a bracket arm 6a of front machine arm 6 and presented in the 25 vertical plane of the rock-arm 42 by which it is engaged. See Figures 1, 3 and 4 of the drawings. This work supporting frame is operated through mechanism hereinafter described for automatically and periodically shifting its position to vary 30 the depth of material presented by its ridge forming member in the path of the needle as hereinafter explained.

The depression of the frame for placing the work upon the frame horn beneath the presser foot is accomplished by the usual treadle 75 connected by a chain or wire 75a with a link 40a hooked to the rear edge of frame 40.

The work supporting frame 40 is extended to the left to form a work supporting horn as is 40 usual with this type of machine. Journaled in the work supporting frame 40 upon the usual conical axial bearing screws 55 is the oscillating 45 conical shaft 61 which carries the "fulling in" ridge forming rib or disk 60 of the usual construction. The usual independently yielding work supporting plates or platens 70 are mounted upon opposite sides of the ridge forming disk 60, each plate 70 being pivoted upon an arm or lever 72 pivoted at 73 upon frame 40 and provided with a 50 spring 72a.

100 is the rigidly mounted presser foot projecting forwardly from the under face of machine arm 5 to a position above the ridge forming disk 60 and the work supporting platens 70. 55 The presser foot is formed with the usual longitudinal slot into which a ridge of the work is pressed by the disk 60 for the action of the stitch forming mechanism.

The shaft 61 has adjustably secured to it a 60 downwardly presented crank arm 62 to which is pivotally connected at 63, a link 64 in turn pivoted at 65 to one arm of a bell crank lever 67 pivotally mounted upon a screw bolt 68 secured to machine frame. The other arm of the bell crank 65 lever 67 is pivoted to the lower end of an eccentric link 69 having a yoke at its upper end encircling the eccentric 14 which is secured upon the shaft 10 alongside of the pulley 11.

It will be observed that the work supporting 70 frame 40 projects rearwardly from the machine arm 6 which is just the reverse of the arrangement of the work supporting frame that has heretofore been employed in this type of machine.

By the eccentric link connection between the 75 power shaft and the shaft 61 of the ridge forming

disk it will be observed that the forward stroke of the disk is effected by an upward thrust upon the rock arm 62. This upward thrust in actively moving the ridge forming disk is exerted in the same direction as the spring induced upward pressure of the work supporting frame which is important in that it cooperates with and does not conflict with the normal spring support of the work supporting frame.

The looper mechanism of the machine is not 10 involved in the present improvement and is not specifically shown, but it will be understood that the same form of looper is employed as has been used in the past in this type of machine, the looper being indicated at 16 carried on the forward end of the looper rod 11 carrying on its rear end a yoke pivoted upon a sleeve which is freely journaled upon the crank pin mounted in the angularly offset arm 80 of the crank disk 13. This looper and its operating mechanism will be 20 clearly understood from my Patent No. 1,467,570 dated September 11, 1923.

The feed mechanism may be of the general type shown in my Patent No. 814,026 dated March 6, 1906, the specific structure of the same being 25 material to the present invention.

125 is the longitudinally movable rocking feed bar actuated at its rear end by the usual eccentric (not shown) upon main shaft 10.

The arm 42 of the work supporting frame 40 30 has secured to it a bracket block 42a through which is threaded an adjustable tappet screw 48 which carries upon its outer end a milled head 49 having a crown wheel collar 50 on which is marked an index scale 51. The crown wheel collar 50 35 operates in peripheral engagement with a small spring plunger 52, which latter is slidably mounted in a socket of the block 42a with its conical outer end in latching engagement with the serrated edge of the collar 50 for the purpose 40 of retaining the screw 48 in the desired adjusted position.

The inner end of the screw 48 engages the vertical tappet face of the short arm 101 of the work controlling bell crank lever which is pivoted upon a set screw 102 threaded into a vertical face 45 of the base frame rib 1a. The other or long arm 103 of said bell crank projects rearwardly from its pivot 102 and is formed in its rear end with a horizontal elongated slot 104 (Figure 7) through 50 which projects a bolt 105. A short rock-shaft 106 extends transversely of the machine below and parallel with the main shaft 10. This rock-shaft 106 is freely journaled in a suitable bearing 107 formed in the frame arm 2 just above the frame 55 base 1. The inner end of said rock-shaft 106 carries a forwardly projecting rock-arm 108 which overlaps the rear end of arm 103. The forward end of rock-arm 108 has an elongated slot 109 55 (Figure 7) in which is adjustably fixed the threaded end of the pin 105 which forms a jointed connection between parts 103 and 108. As shown in Figure 7 of the drawings the pin 105 is formed with an enlarged head which engages the bell 60 crank arm 103 and upon which is freely journaled a hand-operated cam lever 110 in the recessed face of which rests a washer 111 engaged by a set screw 112 by which the member 110 is rotatably confined upon the head of pin 105. The pin 105 has a sliding fit in the slot 104 and is formed 65 with a threaded reduced end which snugly fits and passes through the slot 109 to receive the retaining nut 113 which is screwed upon said threaded end and firmly clamps the pin 105 in the desired adjusted position upon rock-arm 108.

suitable spacing shims or washers indicated at 114 being presented between members 103 and 110 and 103 and 108.

The described construction is such that the pin 105 can be adjusted in the slot of the rock-arm 108 and clamped at the proper distance from the fulcrum shaft 106 to produce the desired extent of the periodic movements of the work support.

The hand lever 110 is formed with a cam 10 peripheral surface, shown particularly at 110a in Figure 8 of the drawings, said periphery being designed to operate upon the upper face of the base frame 1 to shift the position of the inter-engaging arms 103 and 108 into inactive position and lock them in that position as will presently be described.

The rock shaft 106 carries at its outer end an arm 115 having an anti-friction roller 116 which operates in peripheral engagement with a controlling cam 117 mounted upon and rotating with a gear 118 freely journalled upon a stub shaft 119 carried in the machine arm 2 beneath the main shaft 10. This gear 118 meshes with and is driven by a smaller gear 120 keyed to the shaft 10 alongside of the eccentric link 68. The intermeshing gears 118 and 120 may have any desired ratio such as 2:1, 3:1, etc., depending upon the number of impulses it is desired to impart to the system of levers which control the periodic movement of the work support.

It will be observed that the engagement of anti-friction roller 116 of lever 115 with the high portion of cam 117 rocks the long arm 103 of the work controlling bell crank to press upon the tappet screw 48 and slightly lower the ridge forming member 60 by which the work is supported in the path of the needle. This position of the parts is illustrated in Figures 3 and 5, the needle in the stitching operation taking a shallow bite in the work which, when operating upon a hem, will pass through the edge of the hem and skip the lower layer or base material. When the roller of rock-arm 115 is in engagement with the low portion of cam 117 the work support is in position to present the ridge forming member 60 in a slightly higher elevation as shown in Figures 4 and 6, in which position the needle passes through a deeper bite of the material passing through the base material as well as the edge of the turned over layers.

Figures 9 and 10 represent opposite faces of a stitched hem performed on the machine equipped with the improved mechanism. In Figure 9 the inner face and the hem is shown which appears as of ordinary stitching, but, in fact, also has shallow or skip stitches between the deep anchoring stitches. In Figure 10 the right side of the work is shown in which the spaced deep stitches show through.

In Figure 11 a perspective view illustrates the work in which the spaced deep stitches indicated at a pass through the base layer b and the two-ply folded over layers c, c', while the shallow or skip stitches d are shown passing only through the folded over layers c, c'.

The work shown in Figure 12 is the ordinary work of the blind stitch sewing machine with the stitch skipping attachment locked out of operation. The work in this figure is of the ordinary blind stitch type in which the stitches pass entirely through the folded over layers of the hem and engage only the inner surface of the base layer to produce a blind stitch or one that will not show on the right side of the work.

By suitable adjustment of the tappet screw 48 the elevations of the ridge forming member 60 can be controlled to a nicety for both the deep and the shallow stitches. When it is desired to use the machine for its ordinary work with a continuous run of normal stitches the work controlling bell crank 101, 103, is locked against movement in its inoperative position by throwing over the cam lever 110 causing it to engage the face of the machine base 1 and lift the rear end 10 of long arm 103 as well as the forwardly projecting rock-arm 108 which places the anti-friction roller 116 on rock-arm 115 just outside the path of the high portion of cam 117. The work support, when the stitch skipping mechanism is locked out of operation, is in its low position for making shallow stitches so that to perform the ordinary continuous line of deep stitching through the several layers of the work including the base layer the operator adjusts the screw 48 to raise the ridge forming member sufficiently to accomplish the desired depth of penetration of the stitches. In this ordinary sewing operation the rigidly locked lever 101, 103, becomes the stop against which the adjustable tappet screw 48 acts in adjusting the work supporting member and maintaining it in the desired normal position.

I claim:—

1. The combination, in a sewing machine, with a driving shaft, a yielding work support carrying a ridge forming member, and suitable work feeding and stitch forming mechanisms, of a work controlling member in engagement with said work support, operating mechanism between said shaft and said member, and means for disengaging said operating mechanism from said shaft and holding it against movement.

2. The combination, in a sewing machine, with a driving shaft, a pivotally mounted yielding work support carrying a ridge forming member, and suitable work feeding and stitch forming mechanisms, of a pivotally mounted work controlling lever, operating mechanism between said shaft and said lever and adjustable means of engagement arranged between said work support and said lever.

3. The combination, in a sewing machine, with a driving shaft, a pivotally mounted yielding work support carrying a ridge forming member, and suitable work feeding and stitch forming mechanisms, of a pivotally mounted work controlling lever, operating mechanism between said shaft and said lever, adjustable means of engagement arranged between said work support and said lever, and means for disengaging said operating mechanism from said shaft and locking said lever against movement.

4. The combination, in a sewing machine, with a driving shaft, a pivotally mounted yielding work support carrying a ridge forming member, and suitable work feeding and stitch forming mechanisms, of a pivotally mounted work controlling lever, operating mechanism between said shaft and said lever, and an adjustable screw tappet arranged between said work support and said lever.

5. The combination, in a sewing machine, with a driving shaft, a yielding work support, and suitable work feeding and stitch forming mechanisms, of means upon said work support for forming a ridge in the work, a work controlling lever driven by said shaft, an adjustable screw tappet mounted upon said work support and engaging said lever, and means for locking said lever against movement.

6. The combination, in a sewing machine, with a yielding work support carrying a ridge forming member, and suitable work feeding and stitch forming mechanisms, of a pair of interengaging pivoted levers, driving mechanism operating one of said levers, and engaging means between said work support and the other of said levers. 5
7. The combination, in a sewing machine, with a yielding work support carrying a ridge forming member, and suitable work feeding and stitch forming mechanisms, of a power driven rock-arm, a rearwardly extending pivoted lever overlapping said rock-arm, pin and slot engagement between the overlapping portions of said rock-arm and 10 said lever, and engaging means between said work support and said lever. 15
8. The combination, in a sewing machine, with a yielding work support carrying a ridge forming member, and suitable work feeding and stitch forming mechanisms, of a power driven rock-arm, a rearwardly extending pivoted lever overlapping said rock-arm, pin and slot engagement between the overlapping portions of said rock-arm and lever, engaging means between said work support and said lever and a manually adjustable cam lock journaled upon said pin in position to engage the machine frame and hold said connected rock-arm and lever in inactive position. 20
9. The combination, in a sewing machine, with a yielding work support carrying a ridge forming member, and suitable work feeding and stitch 25
- 30
- forming mechanisms, a driving shaft, reducing gears operated by said shaft, a cam actuated by said reducing gears, a rock-shaft carrying a rock-arm presented in operative relation to said cam, a second rock-arm mounted upon said rock-shaft, a pivoted bell crank lever having one arm overlapping said second rock-arm, pin and slot engagement between said overlapping rock-arm and bell crank lever, adjustable means of engagement between said bell crank lever and said work support, and manually operable means for moving said connected rock-arm and bell crank lever to shift the arm out of the path of said cam. 10
10. The combination, in a sewing machine, with a yielding work support carrying a ridge forming member, and suitable work feeding and stitch forming mechanisms, of a power driven rock-arm, a rearwardly extending pivoted lever engaging said work support and overlapping said rock-arm, and a member adjustably mounted upon said rock-arm operatively engaging said lever. 20
11. The combination, in a sewing machine, with a yielding work support carrying a ridge forming member, and suitable work feeding and stitch forming mechanisms, of a power driven rock-arm, a pivotally mounted slotted lever engaging said work support and overlapping said rock-arm, and a pin adjustably mounted upon said rock-arm and operatively engaging the slot of said lever. 25

CHARLES A. DEARBORN.
